STEERING GEAR

Harry W. Pierce, Collingswood, N. J.

Application March 4, 1947, Serial No. 732,209

7 Claims. (Cl. 114—155)

1

This invention relates to gearing for transmitting the movements of an actuating or driving member to a member to be actuated or driven and particularly to the provision of means in such gearing for selecting a reversible or non-reversible gear train as may be desired. The invention is especially advantageous for steering mechanisms of boats and will be so described hereinafter but it will be understood that it is not restricted to this particular application.

In the steering of boats and particularly in the steering of sail boats and auxiliaries it is frequently desirable to know the forces being exerted upon the rudder to determine whether the adjustment of the sails is such as to bring the boat into balance. In the case of the usual tiller the helmsman can determine the balance of the boat by the amount of force which he must exert on the tiller to hold the boat on course and can adjust the sails to counterbalance in greater or less degree the "weather helm" or "lee helm" which he finds to exist. In recent years, however, gear steering mechanisms of non-reversing types have come into popularity on all but smaller classes of boats, and with such mechanisms it is possible for the helmsman to feel the forces acting upon the rudder. The present invention provides a novel steering mechanism which provides all the advantages of both the tiller and the non-reversing gear steering mechanisms now in use.

It is accordingly an object of this invention to provide novel actuating or driving means between an actuating member such as a wheel or helm and an actuated member such as a rudder, said means comprising a plurality of gear trains one of which is reversible or reactive on the actuating member and another being non-reversible, either of said gear trains being available at the selection of the operator.

Another object is to provide a novel steering mechanism for boats which embodies the above means so that the helmsman may readily judge the forces acting upon the rudder by selection of the reversible gear train and thereafter may change to the non-reversible gear train without loss of control of the rudder during the change.

Other and further objects of this invention will appear as the description thereof proceeds.

The accompanying drawings illustrate one embodiment of the invention, but it is to be expressly understood that this embodiment is by way of illustration only and is not to be construed as a limitation of the invention, reference

2

being had to the appended claims for this purpose.

In the drawings, in which like reference numerals indicate like parts,

5 Fig. 1 is a view from above of an embodiment of the invention comprising a boat steering mechanism having two synchronously driven gear trains and a clutch for selecting one or the other of such trains;

10 Fig. 2 is a cross-sectional elevation of the embodiment of Fig. 1; and

Fig. 3 is a partial view of a modification of the embodiment of Fig. 1.

In the several figures, 10 is a suitable frame for 15 supporting the several elements of this embodiment of my invention. Frame 10 may be secured to the wheel box or other parts of the boat as by lags 11 or by other suitable means and provides the lower supporting parts 12, 13, 14 and 15 of four horizontal bearings and a vertical bearing 16. The four horizontal bearings are completed by bearing caps 17, 18, 19 and 20 which are suitably secured to frame 10 as by bolts 21.

20 Mounted in vertical bearing 16 is rudder post 22 carrying rudder 23 and reduced at 24 to fit into a suitable bearing carried at the heel of the deadwood and not here shown as it is not pertinent to the present invention. The upper end of rudder post 22 above bearing 16 is keyed at 25 to worm gear 26 which forms part of a non-reversible gear train for driving the rudder.

25 Bearings 14 and 15 support a stub shaft 27 upon which is mounted worm 28 for engagement with worm gear 26. The teeth of worm gear 26 and the thread of worm 28 have a clearance on the order of .010" for reasons which will more fully appear hereafter. The thread angle and pitch of the worm and worm gear are chosen to provide a self-locking, non-reversible drive. Hence the 30 rudder 23 can be shifted in either direction when stub shaft 27 is rotated by gear 29, but forces on the rudder will not drive back through the worm gear and rotate the stub shaft.

35 Bearings 12 and 13 support the steering shaft 30 which is rotated by any suitable steering device such as wheel 31 secured to its outer end. Rotation of shaft 30 is transmitted to gear 29 by means of gear 32 secured to the inner end of shaft 30 as by key 33. A collar 34 secured to shaft 30 abuts frame 10 to prevent movement of the shaft and gear 32 toward worm gear 26, and abutment of gear 32 against frame 10 prevents movement of shaft 30 in the opposite direction.

40 A bevel gear 35 having a reduced hub 36 is 45 axially bored at 37 for free rotation on shaft 30,

hub 36 being supported in bearing 12. A collar 38 secured to hub 36 prevents movement of gear 35 along shaft 30 to the left by abutment against frame 10, and shoulder 39 formed by the reduced hub 36 prevents movement of gear 35 in the opposite direction also by abutment against frame 10.

Suitable means are provided for clutching the gear 35 to the shaft 30 when desired. In the form shown, the end of hub 36 is notched at 40 to receive an engaging dog 41 of clutch sleeve 42. Sleeve 42 is mounted for movement along shaft 30 and rotates therewith by reason of keys 43 set into shaft 30 and engaging longitudinal keyways 44 formed internally of sleeve 42. A collar 45 is secured to shaft 30 to limit movement of sleeve 42 away from gear 35 but is so positioned that dog 41 can be completely disengaged from notch 40 as shown in the drawings. When clutch sleeve 42 is advanced to engage the clutch, however, shaft 30 drives gear 35 which in turn drives a bevel gear sector 46 secured to rudder post 22 as by key 47. This gear train is reversible or reactive between wheel 31 and rudder 23. The ratios of the several gears are so chosen that bevel gear 35 is driven from the rudder post at the same speed as shaft 30 when the clutch is disengaged.

When installing the gear mechanism, rudder 23 is brought to amidships position and sector 46 is rotated about rudder post 22 until equal portions thereof extend on each side of bevel gear 35. Key 47 is then secured in place to lock sector 46 and rudder post 22 together. Worm gear 26 is then rotated on rudder post 22 until there is equal clearance between its teeth and the worm thread on each side and is then secured in place.

With the apparatus set up and adjusted as above described let it be assumed that the boat is underway with sail set and the helmsman desires to determine the balance of the boat. The helmsman then slides clutch sleeve 42 to the left to engage the clutch dogs 41 in the notches 40 of bevel gear 35. Movement of steering wheel 31 is then transmitted to shaft 30, sleeve 42, gear 35, sector 46 and rudder post 22 to rudder 23, and conversely any forces acting upon rudder 23 are directly transmitted back through the same gear train to wheel 31. The amount of pull transmitted from rudder 23 to wheel 31 indicates to the helmsman the forces acting on rudder 23 and the adjustment of the sails which is required to counter them. Any rotation of shaft 30, either by wheel 31 or by forces acting on rudder 23, also rotates gears 32 and 29, shaft 27 and worm 28, but rotation of the rudder post 22 causes worm gear 26 to rotate simultaneously so that this gear train idles and offers no resistance to the action of the rudder 23 upon steering wheel 31. The clearance on the order of .010" between the teeth of worm 28 and the thread of worm gear 26 is sufficient to allow for play in gears 32 and 29.

When the sails have been suitably adjusted to counterbalance forces acting upon rudder 23, or when it is desired to steer with a non-reversing steering mechanism, clutch sleeve 42 is moved to the right to disengage the clutch. Bevel gear 35 then idles upon shaft 30 and movement of steering wheel 31 is transmitted through shaft 30, gears 32 and 29, shaft 27, worm 28 and worm gear 26 to rudder post 22 and rudder 23, giving the desired non-reversing steering action. Any rotation of rudder post 22 also rotates sector 46 which in turn rotates bevel gear 35 freely upon shaft 30. As pointed out above, the ratios of the

several gears are so chosen that gear 35 rotates at the same speed as shaft 30 and thus the notches 40 are always maintained in alignment with the clutch dogs 41, permitting transfer from one gear train to the other without loss of control of the rudder.

In the embodiment shown in Figs. 1 and 2, worm 28 is provided with a left-hand thread and worm gear 26 is also left-handed so that the direction of rudder movement in relation to rotation of steering wheel 31 may be that now in common usage. If a right-handed worm 28 and worm gear 26 be used, an idler gear must be interposed between gears 32 and 29 to maintain the same relation of movement between rudder and steering wheel. A suitable arrangement for this idler gear is shown diagrammatically in Fig. 3 in which idler gear 50 is mounted upon a shaft 51 to engage gears 32 and 29.

It will now be apparent that by the present invention I have provided a novel apparatus adapted for use as a steering mechanism for boats in which the gear trains may be readily changed by the user, without loss of control of the driven member, from a train permitting evolution of the forces resisting movement of the driven member to a non-reversing gear train and vice versa.

Changes or modifications of the above described illustrative embodiment of my invention may now be suggested to those skilled in the art without departing from my inventive concept. For example clutch sleeve 42 may be provided with mechanical or electrical remote control actuating means when steering is by remote control and various gear trains may be employed to meet the requirements of the various classes of boats. Reference should therefore be had to the appended claims to determine the scope of this invention.

What is claimed is:

1. In apparatus of the class described, means for transmitting rotary motion from a driving member to a member to be driven including reactive and nonreactive transmissions, said means comprising rotatable driving and driven members, nonreversible gearing connecting the driving member with the driven member, reversible gearing for connecting the driving member with the driven member, and clutch means for connecting the driving member with said reversible gearing, the gear ratios between the driving and driven members being the same for both the nonreversible and the reversible gearing, said nonreversible gearing including means providing lost motion between the driving and driven members whereby reaction is transmitted from the driving member through said reversible gearing and clutch means to the driving member and to said nonreversible gearing.

2. Apparatus as defined in claim 1, said clutch means comprising a clutch member connected to said reversible gearing and rotatable relative to the driving member, and a clutch member rotatable with the driving member and movable into engagement with said first clutch member.

3. Apparatus as defined in claim 1, said nonreversible gearing including a worm and worm wheel with clearance between the teeth of the worm wheel and the thread of the worm to provide said lost motion.

4. In boat steering apparatus, a rudder, a steering shaft and a hand steering wheel thereon, and means for transmitting rotation of the steering shaft to the rudder including reactive and nonreactive transmissions, said means comprising

ing nonreversible gearing connecting the steering shaft with the rudder, reversible gearing for connecting the steering shaft with the rudder, and clutch means for connecting the steering shaft with the reversible gearing, the gear ratios between the steering shaft of the rudder being the same for both the reversible and the nonreversible gearing, said nonreversible gearing including means providing lost motion between the steering shaft and rudder whereby reaction is transmitted from the rudder through the reversible gearing and clutch means to the steering shaft and wheel and to the nonreversible gearing.

5. An apparatus as defined in claim 4, said clutch member connected to the reversible gearing and rotatably mounted on the steering shaft, and a clutch member rotatable with the steering shaft and longitudinally movable thereon into engagement with the first clutch member.

6. Apparatus as defined in claim 5, said reversible gearing comprising a toothed sector rotatable with the rudder and spur gearing meshing with said sector and including a pinion ro-

tatably mounted on the gearing shaft and carrying said first clutch member.

7. Apparatus as defined in claim 4, said nonreversible gearing including a worm wheel rotatable with the rudder and a worm meshing with the worm wheel with clearance between the teeth of the worm wheel and the thread of the worm to provide said lost motion.
